COMBINED POWER OPERATED CAN OPENER AND KNIFE SHARPENER

Downer P. Dykes, Lawrence, Kans., assignor to Rival Manufacturing Company, Kansas City, Mo., a corporation of Missouri

Filed Mar. 16, 1964, Ser. No. 79,011

Term of patent 14 years

(Cl. D37—1)

FIG. 1 is a front elevational view of a combined power operated can opener and knife sharpener embodying my new design;

FIG. 2 is a side elevational view looking at the left hand side of FIG. 1;

FIG. 3 is a rear perspective view of same showing the side opposite that seen in FIG. 2; and

FIG. 4 is a fragmentary sectional view taken along the line 4—4 of FIG. 1 in the direction of the arrows.

The corrugated facing at the rear of the unit seen in FIG. 3 is like that seen in FIGS. 1 and 4.

I claim:

The ornamental design for a combined power operated can opener and knife sharpener as shown and described.
